(57) **CLAIM**

The ornamental design for cookware cover, as shown and described.

DESCRIPTION

FIG. 1 is a front, left, top perspective view of a cookware cover showing my design therefor;

FIG. 2 is a top plan view thereof;

FIG. 3 is a bottom plan view thereof;

FIG. 4 is a rear elevational view thereof;

FIG. 5 is a right side elevational view thereof;

FIG. 6 is a front, left, top perspective view of a second embodiment showing my design therefor;

FIG. 7 is a top plan view thereof;

FIG. 8 is a bottom plan view thereof;

FIG. 9 is a rear elevational view thereof; and,

FIG. 10 is a right side elevational view thereof.

Throughout the drawings the broken lines indicate environment and form no part of the design.
